Inventor

By Edmund Talbert

Attorney

UNITED STATES PATENT OFFICE.

JOHN ANDERSON, OF LINCOLN, KANSAS.

WRENCH.

Application filed October 21, 1924. Serial No. 744,941.

To all whom it may concern:

Be it known that JOHN ANDERSON, a citizen of the United States of America, residing at Lincoln, in the county of Lincoln and State of Kansas, has invented new and useful Improvements in Wrenches, of which the following is a specification.

The purpose of the invention is to provide a wrench suitable both for use in the removal of nuts and for operation on pipes and to provide a means for quick adjustment to suit the various sizes of nuts and pipes within a specified range.

With this purpose in view, the invention consists in the construction and combination of parts of which a preferred embodiment is illustrated in the accompanying drawings, wherein:

Figure 1 is a side elevational view of the invention.

Figure 2 is a similar view showing the position of the parts in the adjustment of the same showing the jaw element 2 tilted in dotted lines.

Figure 3 is an edge view.

Figure 4 is a transverse view on the plane indicated by the line 4—4 of Figure 1. Figure 5 is an enlarged detail view of the jaw elements where they are connected together, showing the slot 9 and the stud 5, the stud being in section.

The cooperating jaw elements 1 and 2 are formed as lateral projections respectively of the handle elements 3 and 4, the latter being pivotally connected by means of a fulcrum stud 5 on which the handle elements are secured by means of washers 7 engaged by the peened over extremities 6 of the fulcrum stud. The stud is thus secured in the handle element 4 and pivotally supports the handle element 3, the body portion of the stud engaging in spaced notches 8 formed in the side edge of a slot 9 in and extending longitudinally of the handle element 3.

The body portion 10 of the stud is cross sectionally oval with the major diameter disposed transversely of the handle elements, so that when the jaws are in parallelism, the body portion of the stud may be engaged in a selected notch 8 with the remote end bearing against the straight edge of the slot so as to provide for pivotal movement of the jaw to permit their separating to secure a new hold on the work as the tool is oscillated in the operation of the device.

The jaw 2 has a shoulder portion 11

abutting one edge of the handle element 3 to limit the jaw to a position of parallelism with the jaw 1 and in the adjustment of the device, the jaw 2 may be swung at an angle of divergence with the jaw 1 until the inclined wall 12 abuts the edge of the handle element 3, when the stud will be disengaged from the notch and arranged with the major diameter of the body portion at an angle 63 such that the stud may be slid longitudinally of the slot without engaging any of the notches and when opposite the selected notch may be made to enter the same by swinging the jaw 2 back to a position of 70 parallelism with the jaw 1.

In the adjustment of the device, the inclined bottom edge 12 of the jaw 2 overlapping the handle element 3 and bearing against the edge of the latter, and the body portion 10 of the stud bearing against the straight edge of the slot on which it then has a slide bearing, provide for the ready movement of the two handle elements without the likelihood of the stud engaging in any 80 of the notches until opposite the selected notch, when the relative rocking of the two handle elements effects the desired engagement. In the use of the device on pipes, sufficient pivotal movement is provided by 85 the engagement of the body portion of the stud in a selected notch to permit firm gripping of the pipe by the serrations 14 formed on the facing edges of the jaws.

The extremities of the handle elements 3 90 and 4 are disposed in overlapping relation to permit them readily being grasped by the hand and the remote extremity of the handle element 3 is tapered to a sharp edge to provide a screwdriver bit 15 which may 95 be used with the jaws 1 and 2 serving as a handle when grasped in the hand.

The invention having been described, what is claimed as new and useful is:

A wrench comprising cooperating jaw 100 members both having handle elements, one of which elements is provided with a longitudinally disposed elongated slot with one straight edge and with the other edge provided with spaced notches, and a stud having a body portion of substantially elliptical form in cross section with its major diameter disposed transversely of the handle element when the jaws are in parallelism, said body portion of the stud being adapted to 105 selectively engage in any one of the spaced notches, the jaw member which is a part of

the handle element carrying the stud being provided with a shoulder abutting a longitudinal edge of the other handle element when the jaws are in parallelism and being further provided with a cut away portion on one side face and having an inclined wall abutting the edge of the handle element having the slot when the jaws are disposed at an angle of divergence, the body

portion of the stud in such position being ^{to} disengaged from the notches and with the major diameter of the stud at an inclination to and having a sliding bearing on the straight edge of the slot.

In testimony whereof he affixes his signature.

JOHN ANDERSON.
